In France February 20, 1947

Term of patent 14 years

(Cl. D62—4)

To all whom it may concern:

Be it known that I, Paul Raymond Marchal, citizen of the French Republic, residing at Paris (Seine), France, have invented a new, original, and ornamental Design for Air Conditioning Apparatus, of which the following is a specification, reference being had to the accompanying drawing, forming part thereof.

Fig. 1 is a top plan view of an air conditioning apparatus, showing my new design.

Fig. 2 is a bottom perspective view thereof.

The side of the apparatus not shown by Fig. 2 is substantially like that shown.

The rear of the apparatus not visible on the drawings is substantially plain.

I claim:

The ornamental design for an air conditioning apparatus, as shown and described.

PAUL RAYMOND MARCHAL.
